ATTORNEY

UNITED STATES PATENT OFFICE.

CHARLES MEE, OF ROCHESTER, NEW YORK.

SPOT-LIGHT MOUNT.

1,363,426.

Specification of Letters Patent. Patented Dec. 28, 1920.

Application filed February 2, 1920. Serial No. 355,833.

To all whom it may concern:

Be it known that I, CHARLES MEE, a citizen of the United States, residing at Rochester, in the county of Monroe and State of New York, have invented certain new and useful Improvements in Spot-Light Mounts, of which the following is a specification.

The object of this invention is to provide a new and improved spot light mount by which any make of spot light can be mounted on the dome of the car and operated from the dash and placed in any desired position or turned at any angle that may be desired to illuminate the road.

This and other objects of the invention will be fully illustrated in the drawings, described in the specification and pointed out in the claims at the end thereof.

In the accompanying drawings,

Fig. 1 represents a perspective view of the engine hood and dash board showing the spot light in position thereon.

Fig. 2 is a vertical section through the universal joint on the line 2^x—2^x of Fig. 1.

Fig. 3 is a vertical section through the rocking joint on the dome.

Fig. 4 is a section through the dash, the parts being shown on a larger scale than the corresponding parts in Fig. 1.

Fig. 5 is a section on the line 5^x—5^x of Fig. 4, looking in the direction of the arrow.

Fig. 6 is a detail view of the joint between the stem 16 and arm 15.

Fig. 7 is a detail view of the stem 16 extended through an inclined dome.

In the drawings, like reference numerals indicate like parts.

In the drawings, reference numeral 1 indicates the dash board of the automobile, 2 indicates the engine hood and 3 indicates the dome of the engine hood. On the dash board 1 is placed a washer 4 having an opening centrally therethrough. This washer is thick on top and thin on the bottom. On the top it is threaded to receive the thumb nut 5. Through this washer extends the rod 6 which has a series of notches or recesses 7 on the under side thereof suitable to engage with the edge of the lower half of the washer, by which engagement the rod 6 can be held in any desired position permitting the movement of the rod in and out to any position and the locking thereof in that position. For this purpose the rod can be moved up and down slightly permitting the engagement of the notches with the inner

edge of the washer at various places. The thumb nut 5 is provided to engage with the rod 6 and positively hold it down in its locked engagement. This locked engagement does not prevent or interfere with the turning of the rod 6 on its axis or the tilting of the rod in the washer for a purpose that will presently be described. On the back of the dash board is placed a spring 65 7^a which normally holds the rod 6 down into locked engagement and permits the rod to be readily shifted from one position to another. If the dash board is thick, the back of it is countersunk to permit the tilting or swinging of the rod 6. 70

On the rear end of the rod 6 is provided the T shaped handle 8 by which it may be operated. On the forward end of the rod 6 is provided the block 9 having a recess 75 therein adapted to contain the ball 10 of a ball joint. An adjusting block 11 is provided which engages the ball 10. The block 11 is held in position by a spring 12 and screw 13, which screw may be turned 80 to place any desired tension on the moving block 11 by which a firm engagement may be obtained with the ball joint 10. The ball 10 is on the upper end of a stem 14, which stem has a threaded engagement 85 with the arm 15 and is locked thereon by a nut. The arm 15 is carried on the stem 16 made of $\frac{3}{8}$ " steel tubing. The arm 15 is rigidly fastened at the bottom of the stem in any suitable manner. A pinched joint 90 held closed by a set screw 17 is shown in Fig. 6 and is used for this purpose. The stem 16 extends up through the dome and carries on the top thereof the spot light 18, the shell of which light is clamped thereon 95 by nuts and lock washers carried on the stem 16, both inside and outside of the shell of the lamp.

Where the shell of the lamp is not perpendicular to the stem that passes through it, the tilting of the shell is taken care of by cutting a nut diagonally to correspond to the inclination of the shell and placing one half of the nut below the shell and the other half of the nut above the shell. The upper half of the nut is clamped in place by a lock washer and nut on the stem. On the stem 16 is provided the nut 25 on top of which is supported a tension spring 26. On top of this spring is a flat washer 27 110 with a half of a rubber ball or a cone 28 on top thereof, which ball or cone bears on

the under side of the dome and prevents water leaking through. On top of the dome is provided a washer 29 which is dished to act as a bearing and on top of this washer is placed a rubber ball 30. On top of the ball 30 is placed a washer 31 on top of which rests the nut 32 on the bottom part of the lamp. When the nut 25 is tightened up, the lamp is drawn down on the ball 30.

10 Where the dome of the hood is inclined, the stem 16 passes through it perpendicular thereto and the upper end of the tube is then bent to an upright position as shown in Fig. 7.

15 The operation of my device is as follows:

When it is desired to tilt the lamp down, the operator draws the rod 6 and handle 8 toward him. When he wishes to tilt the

20 lamp up, he pushes the handle and rod away from him. When he wishes to turn the lamp to one side, he moves the handle 8 to the right or left swinging the rod 6 on the dash board as a center and this, in turn, swings 25 the arm 15 and turns stem 16 and turns the lamp as well. The handle can then be twisted to turn the lamp up or down at an angle. In this way, the spot light can be turned to throw its light in any direction.

25 30 The rubber ball 30 and cone 28 and spring 26 hold the lamp firmly in position and prevent rattling and still give sufficient elasticity to permit its movement in any direction desired.

35 I claim:

1. In a spot light mount, the combination of a stem, a spot light mounted thereon, said stem extending through the engine hood of an automobile, a rubber ball surrounding 40 said stem, a dished washer below said ball resting on top of the hood and supporting the light.

2. In a spot light mount, the combination of a stem, a spot light mounted thereon, said 45 stem extending through the engine hood of an automobile, a rubber ball surrounding said stem, a dished washer below said ball resting on top of the hood and supporting the light, a rubber ball below the hood, a washer 50 thereunder and a spring for yieldingly holding it in contact with the hood.

3. In a spot light mount, the combination

of a stem, a spot light mounted thereon, an arm rigid on the bottom of said stem, a second stem rigid on said arm parallel to the first stem, a rod having a universal joint thereon with said second stem, said rod extending through the dash and being movable endwise through the dash and being capable of swinging on the dash. 60

4. In a spot light mount, the combination of a stem, a spot light mounted thereon, an arm rigid on the bottom of said stem, a second stem rigid on said arm parallel to the first stem, a rod having a universal joint thereon with said second stem, said rod extending through the dash and being movable endwise through the dash and being capable of swinging on the dash, means for locking the rod in any of a series of positions. 65

5. In a spot light mount, the combination of a stem, a spot light mounted thereon, an arm rigid on the bottom of said stem, a second stem rigid on said arm parallel to the first stem, a rod having a universal joint thereon with said second stem, said rod extending through the dash and being movable endwise through the dash and being capable of swinging on the dash, said rod being capable of turning the first stem on its axis and then moving it laterally. 75

6. In a spot light mount the combination of a vertical stem, a spot light mounted on the top thereof, means connected to the lower end of the stem for turning the stem on its axis and moving it laterally in a plurality of directions, said stem being supported by and rocking in a plurality of planes on a support surrounding the stem. 85

7. In a spot light mount, the combination of a vertical stem, a spot light mounted on the top thereof, an arm on the bottom of said stem, a second stem on said arm parallel to the first stem, said last named stem being rigid on said arm, a rod extending through the dash and having a universal joint with said last named stem, said first named stem being supported by and rocking in a plurality of planes on a support surrounding the stem. 95 100

In testimony whereof I affix my signature.

CHARLES MEE.
